UNITED STATES PATENT OFFICE.

JOHANN C. TAUBER, OF PLAIN CITY, OHIO.

MATCH-SAFE.

SPECIFICATION forming part of Letters Patent No. 531,660, dated January 1, 1895.

Application filed November 16, 1893. Serial No. 491,090. (No model.)

To all whom it may concern:

Be it known that I, JOHANN C. TAUBER, a citizen of the United States, and a resident of Plain City, county of Madison, and State of Ohio, have invented certain new and useful Improvements in Match-Safes, of which the following is a specification, the principle of the invention being herein explained and the best mode in which I have contemplated applying that principle so as to distinguish it from other inventions.

The annexed drawings and the following description set forth in detail, one mechanical form embodying the invention; such detail construction being but one of various mechanical forms, in which the principle of the invention may be used.

In said annexed drawings—Figure I represents a front view of my improved match safe; Fig. II, a vertical section of the same, and Figs. III and IV sectional detail views illustrating different forms of match guides.

The principal feature of my invention consists in providing means,—in a match safe having an opening from which the matches may be transversely withdrawn,—for preventing the endwise withdrawal of a number of matches, as they drop out through the transverse opening.

A casing, A, is formed with a chamber, A', of a size and shape suitable to hold the sliding portion B of a box of matches, said chamber and box forming together a match receptacle. The front of said chamber is preferably formed by a plate, a, of glass or similar translucent or transparent material, which plate closes the open side of the match box. A removable rod, a', secures the box from the rear, within the chamber, or the back of the casing may be closed by a movable cover. The lower end of the match box rests upon two horizontal ledges, a³, between the facing edges of which is thus formed a slot, a⁴, of a width sufficient to admit of the insertion of a finger. The lower end of the match box is partly cut or torn away to form an opening, b, corresponding to said slot. The front plate a does not extend entirely down to the lower end of the box, but leaves an opening, a⁵, at that point. Said opening is flanked by two forwardly projecting match guides, C, projecting from flanges, C', secured over the

lower portion of the front of the match box chamber. Said guides have sufficient space between them for insertion of at least the 55 thumb and one finger of the hand. The match guides are formed with slots or passages, c, which extend from the lower end of the match box out to the ends of the match guides. Said passages may be either tortuous and obstructed, as illustrated in Figs. II 60 and IV, or they may be straight or curved, as illustrated in Fig. III, and without obstructions. In whatever shape the passages may be, they are of just sufficient width to admit 65 of a match being withdrawn through them, when held in a transverse and horizontal position. The flanges C' are formed with horizontal slots, c', to admit of a match being guided out through the match guides. 70

If desired, a card containing an advertisement or other matter may be inserted between the open front of the match box and the glass plate, as indicated at D, or an advertisement or other matter may be marked 75 upon said plate.

The front A² of the lower portion of the casing is closed, with the exception of an opening, a⁶, beneath the match guide, and a suitable striking surface, E, is preferably provided at the base of the match safe. 80

When the safe is filled, the sliding portion of the usual style of box in which matches are ordinarily packed, is removed from the outer portion of the box, and that end of the 85 sliding box, which will form the lower end when the box is in position, is cut or torn at the middle of its edge to form the notch or opening b. The box is then placed into the match box chamber, with its open side against the glass plate. The box is now secured in place by the rod. Matches may be removed from the box,—one by one,—by inserting two fingers between the match guides,—as indicated by dotted lines in Fig. II,—and withdrawing a match in a transverse and horizontal position. For the purpose of preventing the matches from being drawn endwise from the guides, two cheek pieces, A³, project from the sides of the casing, at sufficient distance 90 from each other and from the match guide to admit of a match of ordinary length passing between them, and to prevent a match passed through the guide from being withdrawn end- 95 100

wise. The match guides will thus prevent more than one match being withdrawn at a time, and will thereby prevent the removal of matches in greater numbers than needed for immediate use, such as is liable to take place, if matches are kept in open receptacles at stores, hotels or other public places.

The glass front of the casing will exhibit the matches, so that the quantity of matches in the safe can be ascertained, and the advertising card will not interfere with the inspection of the contents of the safe, as it does not extend entirely down the front.

Other modes of applying the principle of my invention may be employed for the mode herein explained. Change may therefore be made as regards the mechanism thus disclosed, provided the principles of construction set forth respectively in the following claims are employed.

I therefore particularly point out and distinctly claim as my invention—

1. In a match safe, a casing formed with a chamber adapted to hold the sliding portion of a match box and formed at its lower forward edge with an opening of a size sufficient to admit of the removal of a match in a horizontal position, match guides secured over said opening to project at points sufficiently far apart to permit of the insertion of two fin-

gers and formed with slots extending from the opening in the casing to the outer ends of the guides, and cheek pieces at the ends of the opening in the casing and extending parallel with the guides to prevent endwise removal of a match from the guides, substantially as set forth.

2. In a match safe, a casing formed with a chamber adapted to hold the sliding portion of a match box and formed at its lower forward edge with an opening of a size sufficient to admit of the removal of a match in a horizontal position, match guides secured over said opening to project at points sufficiently far apart to permit of the insertion of two fingers and formed with slots tortuous in a vertical plane and extending from the opening in the casing to the outer ends of the guides, and cheek pieces at the ends of the opening in the casing and extending parallel with the guides to prevent endwise removal of a match from the guides, substantially as set forth.

In testimony that I claim the foregoing to be my invention I have hereunto set my hand this 11th day of November, A. D. 1893.

JOHANN C. TAUBER.
